UNITED STATES PATENT OFFICE.

WILLIAM LESTER BASHFORD, OF BENTON HARBOR, MICHIGAN.

CHURN.

SPECIFICATION forming part of Letters Patent No. 742,823, dated November 3, 1903.

Application filed August 28, 1901. Serial No. 73,576. (No model.)

To all whom it may concern:

Be it known that I, WILLIAM LESTER BASHFORD, a citizen of the United States, and a resident of Benton Harbor, county of Berrien 5 and State of Michigan, have invented a certain new and useful Improvement in Churns, of which the following is a specification.

My invention relates to churning, and has for its object the provision of a simple, compact, 10 and inexpensive construction and to provide certain details and features of construction tending to increase the general efficiency, a special object being, however, to secure increased and more rapid churning action and 15 to provide a construction whereby the parts can be readily and conveniently separated and whereby the dasher can be readily raised and lowered.

To the foregoing and other useful ends the 20 two sections of the churn-dasher are preferably connected with the crank-shaft through the medium of a pair of pitmen, and each pitman is preferably provided with an adjustable crank-bearing, whereby the two dasher-sections 25 are independently adjustable and whereby the dasher as a whole may be raised or lowered for the purpose of varying its position in the churn. Furthermore, the lower ends of the pitmen are connected with the 30 upper ends of the dasher-rod sections by pins, which are preferably mounted on flexible springs secured to the sides of the pitmen and which permit the latter to be readily disconnected from the dasher. The advantages of 35 my invention, together with certain other features of improvement, will, however, hereinafter more fully appear.

In the accompanying drawings, Figure 1 is a side elevation of a churn constructed in accordance with my invention. Fig. 2 is a vertical section on line 2 2 in Fig. 1. Fig. 3 is a horizontal section on line 3 3 in Fig. 2. Fig. 4 is a detail sectional view of the upper end of one of the pitmen, showing the adjustable 45 connection between the pitman and a crank. Fig. 5 is a detail sectional view of the connections between the pitmen and the upper ends of the dasher-rod sections. Figs. 6 and 50 7 are respectively transverse and longitudinal sections through one of the projections or fingers of which the dasher-head is composed. Fig. 8 is a detail of the dasher, illus-

trating the manner in which the two dasher-sections shift relatively or reciprocate in opposite directions.

As thus illustrated, the churn comprises a suitable can or receptacle A, which is adapted to hold the cream, and the dasher B, which latter is arranged for vertical reciprocation within said receptacle A. The said receptacle is preferably provided with a lid or cover a, preferably concave on its upper surface, and constructed with a depending sleeve or tubular bearing a'. The said dasher is split or divided longitudinally and is therefore, as 60 previously explained, composed of two parts or sections. The dasher-rod is therefore composed of two parallel sections b b, arranged to work in the bearing a' and provided at their lower ends with the laterally and horizontally 65 projecting fingers b'. In this way the dasher has a stem which, although composed of two sections, is rod-like in form and arranged for reciprocation in a single bearing, and, furthermore, the churn-dasher has a head composed 70 of two sets of independently-operated projections or fingers. Referring to Figs. 2 and 3, it will be seen that the sections of the dasher are complementary in character and arranged to fit closely together. As stated, 75 80 the tubular bearing depending from the lid or cover is common to both dasher-rod sections, and the opposing surfaces of the latter are preferably flat and of a character to permit free relative shift or sliding movement in 85 opposite directions. Any suitable means or devices may be employed for reciprocating the dasher; but as a simple and effective arrangement the crank-shaft C can be provided with a pair of cranks, and these cranks can 90 be connected with the upper ends of the dasher-rod sections by means of a pair of pitmen D D.

The base or stand for the churn can be provided with an upright E, having its upper end 95 portion adapted to provide a bearing for said shaft and also adapted to provide a supporting-bearing for the hand-wheel F. This hand-wheel, it will be observed, is preferably provided with internal teeth adapted to engage a pinion C' on the shaft C. With this arrangement the shaft C can be rotated by rotating the hand-wheel F, and as the two cranks on said shaft are preferably oppositely 100

arranged the rotation of said hand-wheel will therefore cause the dasher-sections to reciprocate independently and in opposition, so to speak, the two sections sliding up and down 5 and in opposite directions. In other words, with the arrangement shown and described one section of the churn-dasher will descend while the other section moves upwardly. In this way a very rapid and efficient churning 10 action is secured, the agitation of the cream being much greater than heretofore and of a character to insure certain desirable results well known to those skilled in the art.

In order to permit the churn-dasher to be 15 raised and lowered and positioned in accordance with the quantity of cream in the receptacle, the upper ends of the pitmen D are preferably provided with slots d, adapted to receive the clamping-bolts of the two-part 20 bearings G. Referring more particularly to Fig. 4, it will be seen that these bearings G (which, it will be understood, are the bearings for the cranks on the shaft C) are each composed of a couple of blocks g and g', the 25 latter being preferably provided with a projection g², adapted to engage the slot in the pitman. In each case the bearing-blocks are secured together at one end by a screw or bolt g³ and at the other end by means of the 30 relatively longer bolt g⁴, which is, as previously stated, adapted to slide in the slot d. This bolt g⁴ is preferably threaded at its outer end and provided with a nut g⁵, whereby the bearing can be adjusted along the slot in the 35 pitman and whereby the bearing can be clamped at any point on the upper end portion of the pitman. In this way the dasher can be raised and lowered by simply loosening the nuts g⁵ and, as stated, adjusting the 40 crank-bearings relatively to the pitmen.

It is desirable that provision be made for permitting the pitmen to be readily detached from the upper end of the churn-dasher, and to such end the lower ends of the said pitmen 45 are preferably provided with pins d', which, it will be observed, project loosely through holes in the lower ends of the said pitmen, and which are secured to the latter by means of springs d². The upper ends of the dasher-rod sections 50 are preferably provided with openings adapted to receive the inner ends of these said pins d'. When in place, as shown in Fig. 5, these pins d' form pivotal connections between the pitmen and dasher-rod sections. When necessary or desirable, the pitmen can be detached from the dasher-rod sections by simply pulling out the pins d', it being understood that this is possible with the construction shown, the springs d² being sufficiently flexible to 55 permit a slight outward shift on the part of said pins. When the pins are thus partially withdrawn, the pitmen can be swung to one side and the dasher then removed from the churn-receptacle.

60 The head of the dasher can be of any suitable form or construction; but as a matter of further and special improvement the fin-

gers b' are preferably six in number and arranged radially, and each finger is preferably hollow or tubular in form, as shown in Figs. 70 6 and 7. In this way each finger or projection of the dasher-head can be made of thin metal, and it is preferable that each finger be substantially square in cross-section, as shown in Fig. 6. In order to prevent undesirable friction between the dasher-head and churn-receptacle, each finger can be provided at its end with a wooden tip or plug b². These tips can be made adjustable, and in this way they can be arranged to come close to the inner surface of the churn-receptacle, and being made of wood there will be no objectionable friction between these finger-tips and the side walls of the churn-receptacle. 80

With further reference to the peculiar and novel construction of the dasher it will be seen that the churn-receptacle is preferably cylindric in form, and that the form or contour of the dasher-head is therefore substantially round or annular, so as to fit snugly 90 within the said cylindric churn-receptacle. It will also be seen that the two dasher-rod sections are adapted to lie flat against each other and to slide or reciprocate in opposite directions within a single tubular bearing 95 a'. In this way increased efficiency and a better churning action are secured, and at the same time the churn is compact and desirable in form.

100 Preferably the churn-receptacle A is enclosed within a water-tank H, which latter rests upon the base or churn-stand I. In order to prevent lateral movement on the part of the churn-receptacle and at the same time to permit free circulation of the water, a suitable number of the metal loops a² can be secured at the outer surface of the receptacle A. Preferably three of said loops are secured to the bottom of said receptacle, and three similar loops are secured upon the 110 sides of the receptacle at or near its upper end, and also a like number of said loops are secured to the sides of the receptacle at or near its lower end. In this way the said metal loops serve to separate the churn or receptacle from the water-tank H, so as to provide an annular space or chamber around the outside of the receptacle and also so as to provide adequate space between the bottom of the receptacle and the bottom of the water- 115 tank. Owing to their form or shape these loops support and center the receptacle in the water-tank without interfering with the circulation of the water. Any suitable means can be employed for securing the water-tank 120 to the base or churn-stand I; but as a simple and effective arrangement the bead on the bottom of said tank can be engaged by a plurality of cleats secured to the upper surface of said base or churn-stand. The cleats I' I' 125 are preferably secured rigidly to the said base or stand, while the cleat I² is pivoted at one end and provided at its other end with a locking-pin i. This pivoted cleat can be swung 130

back from the tank H by removing the locking-pin i, and when this is done the water tank or receptacle H can be shifted sufficiently to permit it to be lifted or raised clear of the base or stand I. It will be understood that the locking-pin i can be adapted to engage a hole or socket in the base or stand I.

From the foregoing it will be seen that I provide a simple and efficient construction of the churn and that the novel construction of the dasher is adapted to secure quicker and better churning action, due to the increased agitation of the cream. It will also be seen that the various features can be modified or varied to some extent without departing from the spirit of my invention. For this reason I do not limit myself to the exact construction shown and described. Thus it will be seen that the connections between the pitmen and the dasher-rod sections consist of pintles mounted upon springs, which are in turn secured to the pitmen. It will also be seen that the adjustable connections between the pitmen and the cranks involve lugs and bolts projecting from the backs of the crank-bearings and adapted to slide in longitudinal slots formed in the upper end portions of the pitmen. With this arrangement both sections of the dasher can be readily raised or lowered, and, furthermore, the pitmen can be disconnected from the dasher-rod sections without straining the adjustable connections between the crank-bearings and the upper ends of the pitmen.

What I claim as my invention is—

1. A churn comprising a suitable receptacle, a dasher having its head and stem divided longitudinally into two sections, a bearing in which the two sections of the dasher-rod slide or reciprocate upon each other in opposite directions, a crank-shaft arranged above the receptacle, means for manually rotating said crank-shaft, a pair of pitmen, adjustable connections between the crank-shaft and the upper ends of said pitmen, whereby each section of the dasher may be adjusted vertically and independently of the other section, and spring-mounted pintles for connecting the lower ends of said pitmen with the upper ends of the dasher-rod sections, whereby the dasher may be readily disconnected from said pitmen.

2. In a churn, the combination of a suitable receptacle, a dasher in said receptacle, the upper end of the dasher-rod being provided with a transverse socket extending partially through the end of the rod, a crank-shaft, means for rotating said shaft, a pitman having its upper end mounted on said crank-shaft and its lower end provided with a transverse opening, a pintle slidably mounted in said opening and projecting therefrom to an extent to engage said socket, and a leaf-spring secured at one end to the lower portion of said pitman and having its free end secured to the outer end of said pintle, whereby the pitman and dasher-rod can be disconnected by flexing the said spring to an extent to dis-

engage the pintle from the socket, and by then swinging said pitman upwardly about its bearing upon the crank-shaft.

3. In a churn, the combination of a suitable receptacle, a two-part dasher having a head composed of laterally-projecting metal tubes, each tube being rectangular in cross-section and having corners arranged at top and bottom, wooden plugs inserted in the ends of said tubes, a crank-shaft arranged over said dasher and provided with a pair of cranks, bearings mounted on said cranks, pitmen having their upper end portions slotted to receive bolts projecting from the backs of said bearings, springs secured to the lower ends of said pitmen, and pintles secured to the free ends of said pins and adapted to extend through registering openings in the pitmen and sections of the dasher-rod, substantially as and for the purpose set forth.

4. A churn comprising a suitable receptacle, a two-part dasher having its stem or rod divided longitudinally into two sections, a cap for the receptacle provided with a tubular bearing within which the two dasher-rod sections slide or reciprocate upon each other in opposite directions, a horizontally-disposed crank-shaft arranged above the dasher and provided with two oppositely-arranged cranks, a pinion on said crank-shaft, a hand-wheel having internally-arranged teeth, the said pinion being arranged to engage said teeth at the top of the hand-wheel, a two-part bearing mounted upon each crank, a pair of pitmen having their upper end portions slotted longitudinally, bolts secured to said bearings and extending through said slots, whereby each pitman may be adjusted endwise upon its slotted bearing, springs secured to the lower end portions of said pitmen, and pintles secured to the free ends of said springs and extending through registering transverse openings in the lapping end portions of said pitmen and dasher-rod sections, substantially as shown and described.

5. A churn comprising a suitable receptacle, a two-part dasher having a longitudinally split or divided stem or rod, a crank-shaft arranged above said dasher and provided with a pair of oppositely-arranged cranks, a bearing mounted on each crank, pitmen having their upper end portions provided with longitudinal slots adapted to receive bolts and lugs projecting from the backs of said bearings, and pivotal connections between the lower ends of the said pitmen and the upper ends of the sections of the dasher-rod, substantially as and for the purpose set forth.

6. A churn comprising a suitable receptacle, a two-part dasher having its stem or rod divided longitudinally into two sections, a bearing in which the said sections of the dasher-rod slide or reciprocate upon each other in opposite directions, a horizontally-disposed crank-shaft arranged above said dasher and provided with a pair of oppositely-arranged cranks, a bearing mounted upon

each crank, pitmen having their upper end portions mounted to slide endwise upon the said bearings, springs secured to the lower ends of said pitmen, and pintles secured to 5 the free ends of said springs and extending through transverse openings in the pitmen, the projecting end of each pintle being adapted to removably engage a socket or opening in the upper end of one of the dasher-rod sections, substantially as and for the purpose set forth.

7. A churn comprising a suitable receptacle, a two-part dasher having its stem or rod divided longitudinally into two sections, a 15 crank-shaft arranged horizontally above said dasher and provided with a pair of oppositely-arranged cranks, a two-part bearing mounted upon each crank, a pair of pitmen having their lower ends pivotally connected with the 20 two dasher-rod sections, the upper end of each pitman being provided with a longitudinally-extending slot, and bolts securing the two parts of said bearings together and extending through said slots in the pitmen, substantially 25 as and for the purpose set forth.

8. In a churn, the combination of a suitable receptacle, a dasher made in two parts, each section of the dasher-head being provided with laterally-extending metal tubes, wooden 30 plugs inserted in the ends of said tubes, a bearing in which the two sections of the dasher-rod slide or reciprocate upon each

other in opposite directions, a horizontally-disposed crank-shaft arranged above the dasher and provided with a pair of oppositely-arranged cranks, and pitmen having their upper ends adjustably connected to said cranks and their lower ends pivotally and readily removably connected with the upper ends of the dasher-rod sections, substantially as and 40 for the purpose set forth.

9. In a churn, the combination of a suitable receptacle, a dasher having a two-part head, each section of the head being provided with a laterally-projecting and hollow metal tube, 45 each tube being square in cross-section and having its corners arranged at the top and bottom, wooden plugs driven into the ends of said tubes, a cap or cover for the receptacle provided with a depending tube in which the 50 two dasher-rod sections slide or reciprocate upon each other in opposite directions, a horizontally-disposed crank-shaft provided with a pair of cranks, and pitmen having their upper ends adjustably connected with said 55 cranks and their lower ends pivotally connected with the dasher-rod sections, whereby the said metal tubes comprised in the dasher-head may be raised and lowered in the receptacle, substantially as described.

WILLIAM LESTER BASHFORD.
